HEATING APPARATUS

Raymond C. Johnson, Wilkes-Barre, Pa., and Cecil C. Tyrrell, Binghamton, N. Y., assignors to Anthracite Equipment Corporation, Wilkes-Barre, Pa., a corporation of Delaware

Application February 3, 1948, Serial No. 6,036

19 Claims. (Cl. 122--30)

1

This invention relates to heating apparatus and more particularly to a novel, highly effective and advantageous unit for burning solid fuels with especially high efficiency.

An object of the invention is to provide an improved combustion unit for solid fuel in which the fuel is continuously fed through a combustion chamber in contact with the chamber walls, and in which hot gases from the burning fuel are impelled at high velocity along heat transfer walls associated with the chamber. The medium to be heated receives heat not only from the wall portions contacted by the burning fuel, but also from the walls along which the gases are impelled. The high velocity travel of said gases along said walls greatly increases the rate of heat transfer between said gases and said walls; while the rapid impingement of the gases against the wall surface produces a pronounced scrubbing effect which maintains said surfaces clean and further accentuates the heat absorption.

Another and more specific feature of the invention comprises the provision of a single impelling means for drawing air through the fuel bed and thence drawing the combustion gases along the wall surfaces referred to.

Other features of the invention will become apparent from the ensuing description and claims.

In the accompanying drawings:

Fig. 1 is a vertical sectional view of a furnace embodying the invention.

Fig. 2 is a transverse vertical sectional view, on line 2--2 of Fig. 1.

Fig. 3 is a vertical sectional view of a portion of the furnace, on line 3--3 of Fig. 1.

Fig. 4 is a horizontal sectional view on line 4--4 of Fig. 1.

Fig. 5 is a vertical sectional view of another embodiment of the invention.

Fig. 6 is a view in horizontal section, on line 6--6 of Fig. 5.

Fig. 7 is a view in vertical section on line 7--7 of Fig. 5.

Fig. 8 is a vertical sectional view on line 8--8 of Fig. 5.

Referring to Figs. 1-4, the boiler or heater 10 comprises a compartment 11 which provides a combustion chamber for coal or other solid fuel. Said fuel is fed continuously into said chamber by a screw conveyor 12 of conventional type extending through an opening 13 in said chamber. The chamber or compartment 11 is shown open at its lower end, from which the ashes emerge on to a grate 14. The latter extends through

openings 15, 15' in the outer wall 16 of the furnace, through which openings the ashes emerge and drop into a suitable receptacle 17. As the fuel is continuously fed through the opening 13, the pile of fuel above the grate 14 continuously forces the ashes along said grate and out through the opening 15. The fuel extends across the entire cross-sectional area of the lower, or combustion chamber portion, of compartment 11, as shown, so that the walls of said combustion chamber are contacted by burning fuel around their inner periphery for a substantial distance axially of said chamber.

Within the walls of the furnace 10 and surrounding the compartment 11 is water or other fluid medium to be heated, as indicated by the numeral 18. The furnace 10 may be generally cylindrical, as shown in Fig. 4 except that its upper rear portion may be cut away, as shown, and closed by a wall 19 extending in a vertical plane from the top or cover plate 20 to a plate 21 covering the lower portion of said furnace which extends rearwardly from said plate 19. Also, said plate 21 may serve as a mounting for a fan motor 22.

The combustion compartment 11 may similarly be of substantially cylindrical form, except where cut away in its upper rear portion to accommodate a fan compartment 23, which, as shown, may comprise front and rear plates 24, 25, and side plates 26, 27. Said side plates may include lower curved portions 28, 29, secured to or integral with said side plates, and overlapping each other, as shown in Fig. 3, and forming the bottom of said fan compartment 23. At its upper end said compartment 23 may be provided with a curved top plate 30 extending between the plates 24, 25, and having integral with or secured to one of its ends a vertical plate 31 also extending between plates 24, and 25 and forming a wall of a flue or passage 32. At its other end said plate 30 may have integral therewith or secured thereto a vertical extension 33 which also extends between the plates 24, 25 and may be secured in any suitable way to the side plate 27. It will, of course, be understood that the various walls and plates of the furnace and its compartments may be fastened together in any convenient manner, as by welding, bolts, or otherwise.

A plate 34 closes the top of the combustion compartment 11 forwardly of the plate 24, while plate 35 closes the top of said compartment to the rear of said plate 24. An opening 36 in plate 24 provides communication between the upper

end of the combustion compartment 11 and the fan compartment 23.

The front plate 24 of said fan compartment 23 extends downwardly below the plate 35 of the combustion compartment and forms the rear wall of a channel 37, the front wall of which is designated 38. Said channel walls are joined by a bottom wall 39 and a top wall 40, the latter being inclined, as shown, if desired. Said channel 23 fits into vertically extending slots 41, 42 in opposite wall portions of the combustion compartment 11 and thus communicates with opposite portions of the furnace space containing the fluid medium to be heated. Said fluid medium thus extends into said channel 37 and absorbs heat from the aforementioned channel walls 24, 38, 39, and 40. Said channel 37, as shown, extends adjacent the top of the pile of coal or other fuel in the combustion chamber and insures against active burning of the coal in the top of said pile, notwithstanding desirable preheating of the coal by the passage therethrough of hot combustion gases derived from the burning coal in the lower portion of the fuel pile. By preventing burning of said coal in the top of the pile, spalling may be prevented when said coal descends into the extremely hot combustion zone lower in the pile.

A fan 45 is positioned in the compartment 23 and is connected to the motor 22. When said motor is energized, the fan is operated to draw gases at high velocity from the combustion compartment 11 through the opening 36 into the fan blades, whence said gases are whirled around in the fan compartment. The major portion of the gases pass upwardly through the flue 32, which terminates in a suitable point of discharge outside the furnace. Fly ash contained in said gases is thrown against the curved lower surface 29 of the fan compartment by centrifugal action and passes with some of the gases along said surface, then through an opening 46 between the end of said surface and a baffle 47, thence down between surfaces 28 and 29, and finally out through an opening 48 in the plate 35. Said fly ash is thus returned to the top of the fuel pile in the combustion chamber beneath said plate 35, where air velocities are low.

As the fan rotates, it draws air from below the compartment 11 into the lower end of said compartment and thence upwardly through the burning coal or other solid fuel. The fan is desirably of such capacity, and is driven at sufficient velocity, as to draw sufficient air through the fuel to insure substantially complete combustion within the fuel bed, with little or no combustion outside said bed. In other words, for best results it is preferred that the air drawn through the bed be sufficient for the oxygen therein to be converted in the bed substantially completely to CO_2 , with practically no CO emerging from the pile of fuel.

The hot gases emerging from the top of the fuel bed are drawn upwardly by the fan at high velocity between the walls 11 and 38, then laterally between the plates 34 and 40, and thence through the opening 36 and out through the flue, as above described, the fly ash being returned to the top of the fuel bed where it is mixed with incoming fuel.

As the hot combustion gases travel at high velocity along the inner surfaces of the compartment walls 11, 38, 40, and 34, the rate of heat transfer between said gases and said surfaces is greatly increased, as is also the rate of heat

transfer to the fluid medium 18 in contact with said surfaces. Also, said gases, as previously noted, exert a pronounced scrubbing action which maintains said surfaces clean and further increases the rate of heat absorption.

In addition, the gases whirled at high velocity in the fan chamber 23 increase the rate of heat absorption through the surfaces 24, 25, 26, 29, and 30. The heat absorption is further increased by the travel of gases through more than one revolution in the fan chamber before they are discharged.

The portion of the gases emerging from the fan casing through the passage 28 is passed on through the opening 48 into the part of the compartment 11 which overlies the pile of fuel to the left of the channel 37, as viewed in Fig. 1. As previously noted, the gases which pass through said opening 48 contain fly ash. In addition, said gases contain substantial heat which is imparted to the cold fuel emerging from the conveyor 12, so that this incoming fuel is preheated. Said gases emerging from opening 48 descend into the fuel bed under the pressure existing in the fan chamber 23, and also under the influence of the suction created by the fan in the space to the right of the channel 37 as viewed in Fig. 1.

It will thus be seen that the water or other fluid medium 18 receives heat not only through the portions of the compartment walls 11 surrounding the fuel which is burning with substantially complete combustion in the fuel bed, but also from the intensely hot gases drawn from the bed and impelled at high velocity along other portions of said walls 11, and also along the walls 38, 40, 34, 24, 25, 26, 29, and 30. An especially effective high rate of heat absorption is thereby achieved.

It will further be noted that these results are attained, in the embodiment above described, by a single fan which not only draws sufficient air through the fuel bed to insure substantially complete combustion in the bed, but also impels the hot combustion gases upwardly from the bed at high velocity along the surfaces above referred to.

If desired, there may be provided studs or bars 50 of efficient heat conducting material, which bars are shown fitted in openings in the plate 34. Said bars, as shown, extend from the interior of the combustion compartment 11 into the fluid medium 18. These bars provide additional heat absorbing surfaces, extracting further heat from the gases before they reach the fan 45.

In the embodiment shown in Figs. 5-8, the furnace 60 comprises a combustion compartment 61, open at its lower end and having an intermediate opening 62 for receiving coal or other solid fuel. The fuel may be fed continuously by a screw conveyor into a hopper 63, from which it flows through opening 62 into the combustion compartment. The ashes pass through the bottom of said compartment on to a grate 64, from which they drop into a receptacle 65. As in the embodiment shown in Figs. 1-4, the fuel extends across the entire cross-sectional area of the lower portion of compartment 61, so that the walls of the combustion chamber are contacted by burning fuel around their inner periphery for a substantial distance axially of said chamber.

The compartment 61 may be of cylindrical form as illustrated. Its upper end is closed by a suitable cover 66. Said compartment is further provided with an opening 67 for the passage of gases from said compartment into a hori-

horizontal duct or chamber 68, at one end of which is positioned the fan 69.

Communicating with the periphery of the fan 69 is an annular duct or passage 71, formed by concentric annular shells 72, 73. The shell 72 is fitted into an opening in the rear wall 70 of the furnace, and is closed at its outer end by a plate 72'. The cylindrical shell 73 is spaced from and supported by the duct 68, through an annular member 74 surrounding said duct, as shown. At its opposite end, said shell 73 is joined to the casing 72 in any suitable manner, as by an end plate 75, which has an opening 76 communicating with the duct 71. The latter is formed of converging walls and extends to an opening 78 (Figs. 6 and 7) in a vertical flue 79. Said duct 77 may be secured by welding or bolts, or in any other desired manner, to the flue 79 and the shells 71, 73, or plate 75.

The shaft 80 of the fan 69 passes through a bearing in the plate 72' and is driven by a motor 81. The space within the outer furnace walls, and surrounding the compartment 61 and ducts 68, 71, and 75, contains water or other fluid medium to be heated.

In operation, the fan 69 draws air upwardly from below the compartment 61 into the lower end of said compartment and thence upwardly through the burning coal or other solid fuel. It will of course be understood that provision for the entrance of air through the portion of the furnace below said compartment 61 may readily be made by providing suitable openings, variable in size if desired, either in the door 60' or elsewhere in the furnace walls. As in the case of the fan 45, the fan 69 is preferably of such capacity, and is driven at sufficient velocity, to draw enough air through the fuel to insure substantially complete combustion within the fuel bed, so that the oxygen in the air is converted substantially completely to CO₂ within the bed, with practically no CO emerging from the pile of fuel.

As the hot gases evolved from the burning fuel ascend through the upper portion of the bed under the action of the fan 69, they preheat the fuel in the top of the bed. The hot gases emerging from the top of the fuel bed are thence drawn upwardly by said fan at high velocity through the interior of the compartment 61, and thence through the interior of the horizontal passage 68. The gases are thence impelled outwardly by the fan blades into the annular duct or passage 71. Under the rotary action of the fan blades said gases are set into rotation at high velocity in said duct, while at the same time they travel longitudinally therein and then pass through opening 76 into the duct 77. From the latter, said gases pass into the flue 79 and thence upwardly therethrough to a discharge point 85 outside the furnace.

Preferably, the gases are introduced tangentially into the flue 79. The particles of fly ash, through centrifugal force, remain adjacent the outer portions of the space within said flue. They gradually settle downwardly, through passage 86 and opening 87, into the ashes on the grate and are carried therewith into the ash receptacle. The flue 79 thus serves additionally as a fly-ash separator.

As an illustration of the speed of rotation imparted to the gases in the duct 71, the fan rotor in typical examples may revolve at speeds of from 1725 to 3450 revolutions per minute, or peripheral speeds of from 4500 to 9000. The gases emerging from the fan periphery are thus re-

volving at approximately this speed. This high velocity of rotation of the gases in the duct 71 markedly increases the rate of heat transfer to the fluid medium which surrounds both the outer shell 72 and the inner shell 73 of said duct. In addition, the high speed of travel of the gases through duct 68 toward the fan increases the rate of heat transfer between that duct and the fluid medium surrounding it. Increased heat transfer is also obtained through the walls of the compartment 61 above the fuel bed as the gases travel at high velocity through said compartment. The fluid medium thus receives heat at a greatly increased transfer rate from the hot gases drawn from the fuel bed; and this heat is additional to that absorbed by said medium through the portion of the compartment walls 61 which surround the burning fuel.

It should further be noted that the heat absorption is additionally increased by the fact that the gases make several revolutions around the duct or chamber 71 before they are discharged through the outlet duct 77. This is equivalent to passing them over a greater surface area. In addition, said gases, due to the fan rotation, travel through said chamber 71 in a spiral path, which is equivalent to providing them with a greater length of travel and time of contact, thus further increasing absorption of their heat.

As previously observed, the heat-absorbing surfaces are all arranged so that the gases are continuously wiping them. This is carried out even into the fly-ash separator in Figs. 6 and 7. It will be noted that, as the gases are forced out of the chamber 71 through duct 77 into flue 79, they are so directed into said flue as to spiral around therein, intimately contacting its heat transfer surfaces.

The terms and expressions which we have employed are used as terms of description and not of limitation, and we have no intention, in the use of such terms and expressions, of excluding any equivalents of the features shown and described or portions thereof, but recognize that various modifications are possible within the scope of the invention claimed.

We claim:

1. Heating apparatus for burning solid fuel to produce combustion with substantially no CO in the resulting gases and obtaining a high rate of heat transfer to a fluid medium, said apparatus comprising a fuel-receiving chamber having an opening in one portion thereof for receiving solid fuel and an opening in another portion for the discharge of consumed fuel, said chamber between said openings comprising a continuous fuel-enclosing wall for contacting said fuel around the inner surface of said wall and confining said fuel in an elongated column, means for continuously supplying solid fuel into said chamber through said receiving opening and concurrently exerting a force through said fuel column upon the consumed fuel for ejecting the latter through said discharge opening, a portion of said fuel-confining wall between said receiving and discharge openings defining a combustion zone in a portion of said fuel column confined by said inner surface of said wall, fan means for continuously forcing air through said combustion zone in quantity sufficient for substantially complete combustion in said fuel bed and for thence forcing the hot gaseous products of said combustion through the end portion of said confined fuel column remote from said discharge opening to subject incoming fresh fuel to the

heat of said gases, passage means communicating with said fuel-receiving chamber beyond said remote end of said fuel bed for conducting said gaseous combustion products to a point of discharge, and compartment means for maintaining a fluid medium in heat transfer relation with said fuel column and with said passage means, said passage means including a chamber containing said fan means and located in heat transfer relation with said fluid medium.

2. Heating apparatus as defined by claim 1 wherein said chamber containing said fan means has an arcuate wall adjacent the blades of said fan means whereby gases are impelled by said fan means over said wall with a rotary motion before discharge of said gases from said chamber.

3. Heating apparatus as defined by claim 1, wherein said fan means draws air and combustion gases through the fuel bed countercurrent to the travel of the latter in said fuel-receiving chamber.

4. Heating apparatus as defined by claim 1, wherein the space enclosed by said fuel-enclosing wall is of substantially uniform cross-sectional area between said fuel-receiving and fuel-discharge openings.

5. Heating apparatus as defined by claim 1, wherein the fan means draws air into the fuel bed in the direction of the longitudinal axis of said bed, and also draws combustion gases through said bed in said direction.

6. Heating apparatus as defined by claim 1, wherein said passage means comprises portions extending upwardly and laterally from said fuel receiving chamber.

7. Heating apparatus as defined by claim 1, wherein said passage means has a portion extending upwardly from said fuel-receiving chamber for receiving gases emerging from said remote end of said confined fuel column and also has a lateral extension communicating with the upper end of said upwardly extending passage portion, said fan means is in direct communication with said lateral extension, and said passage means also has a portion for receiving gases through said fan and directing said gases to a gas discharge opening.

8. Heating apparatus as defined by claim 1, wherein said passage means has a portion extending upwardly from said fuel-receiving chamber for receiving gases emerging from said remote end of said confined fuel column and also has a lateral extension communicating with the upper end of said upwardly extending passage portion, and wherein the chamber for said fan means is provided at an end of said lateral extension and in communication therewith, and a vertically extending passage has its lower end in communication with the top of said fan chamber and extends to a gas discharge opening, said fan means being located in the last-mentioned chamber for drawing gases through the first mentioned passage means and thence impelling them through the last mentioned passage to said gas discharge opening.

9. Heating apparatus as defined by claim 1, wherein said passage means has a portion extending upwardly from said fuel-receiving chamber for receiving gases emerging from said remote end of said confined fuel column and also has a lateral extension communicating with the upper end of said upwardly extending passage portion, and wherein the chamber for said fan means is provided in communication with said lateral extension, a second lateral passage being provided

which surrounds the lateral extension of the first named passage means and forms an extension of said fan chamber, and said fan means being located in said fan chamber for driving combustion gases through said first mentioned passage means and thence impelling them through said second lateral passage towards a gas discharge opening communicating with said second lateral passage.

10. Heating apparatus as defined by claim 1, wherein said passage means has a portion extending upwardly from said fuel-receiving chamber for receiving gases emerging from said remote end of said confined fuel column and also has a lateral extension, said compartment for containing a fluid medium surrounding both said upwardly extending portion and said lateral extension of said passage means, said chamber for said fan means being in communication with said lateral extension, a second lateral passage being provided which surrounds the lateral extension of the first mentioned passage means and forms an extension of said chamber for said fan means, said second lateral passage being in communication with a gas discharge opening.

11. Heating apparatus as defined by claim 10, wherein said second laterally extending passage surrounding the first mentioned laterally extending passage is spaced therefrom, and means are provided for maintaining a fluid medium in the space between said laterally extending passages.

12. Heating apparatus as defined by claim 10, wherein fly ash receiving means communicates with said second lateral passage.

13. Heating apparatus as defined by claim 8, wherein other passage means are provided for conducting fly ash from said fan chamber and baffle means are provided between said other passage means and said vertically extending passage for diverting fly ash into said other passage means.

14. Heating apparatus as defined by claim 1, wherein said passage means has a portion extending upwardly from said fuel-receiving chamber for receiving gases emerging from said remote end of said confined fuel column and also has a lateral extension, a second laterally extending passage being provided which surrounds the first mentioned lateral passage, said fan means being positioned for driving gases through said upwardly extending passage and the first mentioned lateral passage and thence impelling said gases rotatively into said second lateral passage, and said compartment means for the fluid medium maintaining the latter in heat exchange relation with both said laterally extending passages and said upwardly extending passage.

15. Heating apparatus as defined by claim 14, wherein the second laterally extending passage is in communication with the periphery of said fan for receiving gases impelled rotatively from said periphery.

16. Heating apparatus as defined by claim 1, wherein said fan means is interposed between portions of said passage means for continuously drawing air into said fuel bed and thence drawing the resultant combustion gases into one portion of said passage means and causing said gases to travel spirally in the other portion of said passage means.

17. Heating apparatus as defined by claim 1, wherein said fan means is interposed between portions of said passage means for continuously drawing air into said fuel bed and thence drawing the resultant combustion gases into one por-

tion of said passage means and impelling said gases through a plurality of revolutions in the other portion of said passage means prior to their discharge therefrom.

18. Heating apparatus as defined by claim 1, wherein said fan means continuously forces combustion gases through said passage means in wiping contact with the surfaces thereof.

19. Apparatus as defined in claim 1, wherein said fan means impels gas through said passage means at a velocity sufficiently high to accelerate substantially the rate of heat transfer to said fluid medium.
